(57) **CLAIM**

The ornamental design for a vehicle light bar, as shown and described.

DESCRIPTION

FIG. 1 is a perspective view of a vehicle light bar; FIG. 2 is a front view of the vehicle light bar; FIG. 3 is a rear view of the vehicle light bar; FIG. 4 is a right-side view of the vehicle light bar; FIG. 5 is a left-side view of the vehicle light bar; FIG. 6 is a top view of the vehicle light bar; FIG. 7 is a bottom view of the vehicle light bar; and, FIG. 8 is a perspective view of the vehicle light bar installed on a roof of a vehicle.

The broken lines shown in FIGS. 1-7 illustrate portions of the vehicle light bar in which the design is embodied that form no part of the claimed design. The dot-dash broken lines in FIG. 8 depict environmental subject matter that forms no part of the claimed design.
